(57) **CLAIM**

The ornamental design for a watch face, as shown and described.

DESCRIPTION

FIG. 1 is a front perspective view of the watch face of the present invention;

FIG. 2 is an angled, front perspective view thereof;

FIG. 3 is a front elevational view thereof; and,

FIG. 4 is another front elevational view thereof.

The broken line showings of logos, wristband, and knobs, where used, are for illustrative purposes only and form no part of the claimed design.

1 Claim, 4 Drawing Sheets
